UNITED STATES PATENT OFFICE.

JOSEPH C. WARNER, OF CORBIN, KANSAS, ASSIGNOR OF ONE-HALF TO
LAFE BURGER, OF CORBIN, KANSAS

SPRING-WHEEL.

No. 828,354.

Specification of Letters Patent.

Patented Aug. 14, 1906.

Application filed December 4, 1905. Serial No. 280,290

To all whom it may concern:

Be it known that I, JOSEPH C. WARNER, a citizen of the United States, residing at Corbin, in the county of Sumner and State of Kansas, have invented certain new and useful Improvements in Spring-Wheels, of which the following is a specification.

This invention relates to wheels, and more particularly to that type which are so constructed as to derive their resiliency from metallic springs.

In common practice pneumatic tires are very largely employed, but are very objectionable, owing to the fact that they are very expensive, must be frequently replaced, and, furthermore, are very unreliable, since they are liable to be punctured at any time without the slightest warning.

The object of this invention has accordingly been to provide a spring-wheel which is very simple in construction and can therefore be manufactured at a very slight increase in cost over the ordinary form of wheel and which will be very durable in operation.

For a full description of the invention and the merits thereof and also to acquire a knowledge of the details of construction of the means for effecting the result reference is to be had to the following description and accompanying drawings, in which—

Figure 1 is a side elevation of a wheel constructed in accordance with my invention. Fig. 2 is a side view, one of the side plates being removed and parts being broken away to more clearly illustrate the details of construction; and Fig. 3 is a transverse sectional view.

Corresponding and like parts are referred to in the following description and indicated in all the views of the drawings by the same reference characters.

The frame of the wheel comprises, essentially, an outer rim 1 and an inner concentric rim 2, which are rigidly connected by means of a number of spokes 3, said spokes being preferably disposed in a radial direction. Plates or spiders 4 fit loosely against opposite sides of the inner rim 2 and are provided with a series of radial arms or links 5, which are pivotally connected thereto and extend outwardly on both sides of the spokes 3. The extremities of each pair of these arms 5 are connected by means of a transverse member 6, which is provided with an opening 7,

through which the spokes 3 pass. This member 6 is preferably formed out of a piece of sheet metal which has its opposite edges bent inwardly to form flanges 8, which are pivotally secured to the arms 5 by any suitable fastening means. Tubular members 9 are secured in the openings 7 and form guide members, which slide freely upon the spokes 3. A number of coil-springs 10 are interposed between the inner rim 2 and the transverse members 6 and form an elastic connection between the plates 4 and the frame of the wheel. These springs are preferably fastened at both ends, so that they can act both under compression and tension. The plates 4 are provided with centrally-disposed openings, by means of which the axle-bearing 12 is secured in position.

In the operation of the device it will be apparent that the weight of the vehicle will act through the axle to push downwardly upon the plates 4. This will cause the upper springs 10 to be thrown under compression and the lower springs under tension. It will thus be seen that the springs 10 form a resilient connection between the axle-bearing 12 and the frame of the wheel and that they will break any jars and will fulfil all the functions of a pneumatic tire.

Having thus described the invention, what is claimed as new is—

1. In a wheel, the combination of an outer rim, an inner rim, spokes connecting the outer and inner rims, a plate fitting loosely against the inner rim, members slidably mounted upon the spokes, connecting means between the slidably-mounted members and the plate, and springs interposed between the inner rim and the slidably-mounted members.

2. In a wheel, the combination of an outer rim, an inner rim, spokes connecting the two rims, a plate fitting loosely against the inner rim, arms pivotally connected to the said plate and extending outwardly along the spokes, members slidably mounted upon the spokes and loosely connected to the said arms, and springs interposed between the inner rim and the slidably-mounted members.

3. In a wheel, the combination of an outer rim, an inner rim, spokes connecting the two rims, plates fitting loosely against opposite sides of the inner rim, arms pivotally connected to the plates and extending outwardly

along the opposite sides of the spokes, transverse members connecting each pair of arms and provided with an opening through which the spokes pass, and springs interposed between the inner rim and the transverse members.

4. In a wheel, the combination of an outer rim, an inner rim, spokes connecting the two rims, a plate fitting loosely against the inner rim, arms pivotally connected to the plate and projecting outwardly along the spokes, transverse members loosely connected to said arms and provided with openings through which the spokes pass, bearings secured in said openings and slidably mounted upon the spokes, and springs interposed between the inner rim and the transverse members.

5. In a wheel, the combination of an outer

rim, an inner rim, spokes connecting the two rims, plates fitting loosely against opposite sides of the inner rim, arms pivotally connected to the said plates and projecting outwardly along the spokes, transverse members connecting each pair of arms and having a movable connection therewith, tubular bearings secured to the transverse members and slidably mounted upon the spokes, and spring members interposed between the inner rim and the transverse members.

In testimony whereof I affix my signature in presence of two witnesses.

JOSEPH C. WARNER. [L. s.]
